(57) **ABSTRACT**

Display assemblies with an incorporated lift box are disclosed, along with related systems and methods. The display assembly includes a common structure including and/or forming the lift box in a base thereof. An electronic display subassembly is connected to the common structure and includes a cover layer and an electronic display layer. Two such display assemblies may be arranged at a common surface such that an open end of the lift boxes faces in an at least substantially same direction. Forks of a forklift or pallet jack may be moved into the lift boxes for transporting the display assemblies together.

DISPLAY ASSEMBLIES WITH
INCORPORATED LIFT BOXESCROSS-REFERENCE TO RELATED
APPLICATIONS

This application claims the benefit of U.S. provisional patent application Ser. No. 63/611,591 filed Dec. 18, 2023, the disclosures of which are hereby incorporated by reference as if fully restated herein.

TECHNICAL FIELD

Exemplary embodiments relate generally to display assemblies with incorporated lift boxes and systems and methods related to the same.

BACKGROUND AND SUMMARY OF THE
INVENTION

Digital out of Home (“DOOH”) advertising is becoming increasingly popular. DOOH advertising units include an electronic display, typically at least partially enclosed within a ruggedized housing. This may help the units withstand various environmental conditions such as severe weather, solar loading, user interactions, and the like. Examples of such DOOH units include the BOLDVU® product available from Manufacturing Resources International, Inc. of Alpharetta Georgia (mri-inc.net).

These DOOH units may be relatively large display assemblies which are configured for mounting to a sidewalk, wall, or other surface. Sometimes, such display assemblies (fully or partially assembled) require shipping relatively long distances, such as across an ocean and/or to one or more different countries or continents, for final delivery and/or installation. Sometimes the display assemblies must be placed into a shipping container or other transportation medium for transport on a vehicle such as a cargo ship, airplane, railway, flatbed truck, combinations thereof, or the like. Sometimes transportation requires multiple transportation vehicles and/or media, with intermediary transportation, loading, and/or unloading, for example. Regardless, it is desirable to efficiently pack such display assemblies when shipping, such as to maximize available space for shipping display assemblies or other items.

These display assemblies (hereinafter also sometimes “units”) are relatively large and heavy. Thus, it may be desirable to accomplish further transportation (e.g., loading, unloading, movement) by intermediary vehicle such as a forklift and/or pallet jack (manual or autonomous) for example.

Display assemblies which include incorporated lift boxes are provided. Such units may each include a lift box located at a lower portion of the unit, such as at a bottom portion of a structural framework. Two display assemblies may be aligned, such as by mounting to a common surface to face in a first common direction, such that openings in the lift boxes are aligned in a second common direction to receive forks of an intermediary transportation vehicle (e.g., forklift and/or pallet jack). This may provide ease of transportation and/or efficient packing.

The lift boxes may form part of a base for the units, which may elevate the structural framework and/or electronic display subassemblies of the units from a ground or other surface when the units are installed. The bases may be used for installation of the units, such as at a sidewalk, parking

2

lot, or other ground surface, for example. In this way, the lift boxes may serve multiple purposes and/or be integrated with the units.

In exemplary embodiments, each of the units comprise a first, forward facing electronic display subassembly and a second, rearward facing electronic display subassembly. Each of the lift boxes in such embodiments may be located at least partially between the first and second electronic display subassemblies for the units and include an opening which faces in a common direction. Additional equipment (e.g., electric vehicle chargers, thermal management equipment, computer equipment, wireless communications equipment, combinations thereof, or the like) may also be provided at the units.

Further features and advantages of the systems and methods disclosed herein, as well as the structure and operation of various aspects of the present disclosure, are described in detail below with reference to the accompanying figures.

20 BRIEF DESCRIPTION OF THE DRAWINGS

In addition to the features mentioned above, other aspects of the present invention will be readily apparent from the following descriptions of the drawings and exemplary embodiments, wherein like reference numerals across the several views refer to identical, similar, or equivalent features, and wherein:

FIG. 1 is a perspective view of two exemplary units mounted at a common surface in an exemplary configuration with an approaching, exemplary pallet jack;

FIG. 2 is the perspective view of FIG. 1 with forks of the pallet jack inserted into lift boxes of the units for transportation;

FIG. 3 is a front view of the FIG. 1 embodiment; and FIG. 4 is a right-side view of the FIG. 1 embodiment.

25 DETAILED DESCRIPTION OF EXEMPLARY
EMBODIMENT(S)

40 Various embodiments of the present invention will now be described in detail with reference to the accompanying drawings. In the following description, specific details such as detailed configuration and components are merely provided to assist the overall understanding of these embodiments of the present invention. Therefore, it should be apparent to those skilled in the art that various changes and modifications of the embodiments described herein can be made without departing from the scope and spirit of the present invention. In addition, descriptions of well-known functions and constructions are omitted for clarity and conciseness.

45 Embodiments of the invention are described herein with reference to illustrations of idealized embodiments (and intermediate structures) of the invention. As such, variations from the shapes of the illustrations as a result, for example, of manufacturing techniques and/or tolerances, are to be expected. Thus, embodiments of the invention should not be construed as limited to the particular shapes of regions illustrated herein but are to include deviations in shapes that result, for example, from manufacturing.

50 FIG. 1 through FIG. 4 illustrate an exemplary transportation system 50 for display assemblies 10. Individual ones of the display assemblies 10 may be referred to herein with a letter modifier, e.g., 10A, 10B. The transportation system 50 may be used to transport multiple display assemblies 10, preferably provided in pairs, more preferably two display assemblies 10, without limitation. The units 10, in exem-

plary embodiments without limitation, may include those available from Manufacturing Resources International, Inc. of Alpharetta Georgia (mri-inc.net) and/or components thereof. For example, without limitation, the units **10** may comprise BOLDVU® displays, which may form the display subassemblies **12**, at least in part, and/or part of, or all of, the units **10**.

The display assemblies **10** may each comprise one or more electronic display subassemblies **12**. The electronic display subassemblies **12** may be attached to a common structure **14**. The common structure **14** of a respective one of the display assemblies **10** may be referred to herein with a letter modifier, e.g., **14A**, **14B**. Each of the electronic display subassemblies **12** may comprise an electronic display layer (e.g., liquid crystal, OLED), a cover layer(s), a backlight (direct or edge lit), optical films or layers (e.g., polarizers, anti-reflection films or coatings, dual brightness enhancement films, combinations thereof, or the like), combinations thereof, or the like.

The units **10** may comprise additional equipment **26** such as, but not limited to, electric vehicle charging equipment, touch screens, telephonic equipment, video communication equipment, cameras, sensors, thermal management subassemblies (e.g., airflow pathways, fans, heat exchangers, air conditioners, filters, combinations thereof, or the like), communications equipment (e.g., radio equipment, wireless routers, modems, combinations thereof, or the like), servers, computing devices, combinations thereof, or the like. Some or all of such equipment **26** and/or components thereof, may be located internal to, and/or external to, said structure **14**. The equipment **26** of a respective one of the display assemblies **10** may be referred to herein with a letter modifier, e.g., **26A**, **26B**.

The structure **14** may comprise one or more members, housings, cladding, struts, combinations thereof, or the like. The structure **14** may provide a structural framework for supporting and/or protecting the electronic display subassemblies **12** and/or the additional equipment **26**. At least the electronic display subassemblies **12** may be mounted to the structure **14** in a manner which permits the subassemblies **12** to be moved outward, such as for accessing a rear of the subassemblies **12** and/or interior of the units **10**, including for example without limitation, the additional equipment **26** (e.g., for servicing, repair, replacement, etc.).

The units **10** may each comprise multiple electronic display assemblies **12A-D**. Each unit **10** may comprise electronic display assemblies **12** positioned on either side of the structure **14**, such as to face in different, preferably opposing, directions. Other size, shape, number, and/or arrangement of electronic display assemblies **12** may be utilized.

The units **10** may comprise a base **16**. The base **16** may be part of the structure **14** (e.g., forming a lower portion thereof). The base **16** may support a remaining portion of the structure **14** and/or unit **10** from a ground or other surface.

The units **10** may optionally comprise an open area **15**. In exemplary embodiments, without limitation, the open area **15** may be located at a lower portion of the structure **14**, such as below the electronic display subassembly(ies) **12** and above the base **16** of a given unit **10**. This may allow for airflow and/or visual sightlines through the unit **10**. The open area **15** may be entirely unobstructed in exemplary embodiments.

Multiple units **10** may be mounted to a common surface **32**, such as for transportation, packaging, and/or shipping purposes. In exemplary embodiments, without limitation, the units **10** are mounted to a given common surface **32** in

one or more pairs, preferably two units **10** to a given common surface **32**. The common surface **32** may comprise a metal plate, for example. Mounting may be accomplished by bolting or other temporary fastening, for example.

Each of the units **10** may comprise a lift box **18**. Individual ones of the lift boxes **18** may be referred to herein with a letter modifier, e.g., **18A**, **18B**. In exemplary embodiments, the lift boxes **18** form part of the base **16** and/or structure **14**. Preferably, each of the lift boxes **18** form part of and/or are provided in one of the bases **16**. Each of the bases **16** may comprise a platform **20**. The platform **20** may form part of the lift box **18** or be separate therefrom. One or more feet **22** may optionally extend from the platform **20**. For example, front and rear feet **22A**, **22B** may be provided for each unit **10**. Any number and/or arrangement of feet **22** may be provided.

Each of the lift boxes **18** may comprise an opening **24**. Preferably, each of the lift boxes **18** has a single opening **24** on one end thereof. However, each of the lift boxes **18** may have multiple openings **24**, such as on either end thereof. Individual ones of the openings **24** may be referred to herein with a letter modifier, e.g., **24A**, **24B**. The lift boxes **18** may each comprise a cuboid shaped void.

The openings **24** may be configured to receive forks **30** of an intermediary transportation vehicle **28**. Individual ones of the forks **30** may be referred to herein with a letter modifier, e.g., **30A**, **30B**. The openings **24** may be permanently opened ends of the lift box **18**, for example. In other exemplary embodiments, without limitation, the openings **24** may be subsequently closed, such as after transportation to a final destination, during or after installation, combinations thereof, or the like. For example, the openings **24** may be closed by adding a plug, welding a cover plate thereon, combinations thereof, or the like. In still other exemplary embodiments, without limitation, the lift boxes **18** may include an enclosure mechanism, such as a spring-hinged door by way of non-limiting example. In this way, the openings **24** may be closed when not in use.

In exemplary embodiments, the units **10** are mounted in alignment such that the electronic display subassembly(ies) **12** face in a respective, common direction. For example, an electronic display subassembly **12A** of a first unit **10A** faces in a first direction **D1** and an electronic display subassembly **12C** of a second unit **10B** faces in the first direction **D1**. Where the units **10** employ multiple electronic display subassemblies **12**, each may face in a same, common direction. For example, a second electronic display **12B** of the first unit **10A** and a second electronic display **12D** of the second unit **10B** may each face in a second common direction **D2**. The second common direction **D2** may oppose the first common direction **D1** in exemplary embodiments, without limitation.

In this fashion, lift boxes **18A**, **18B** of the multiple units **10A**, **10B** may be substantially (e.g., within 20%) aligned, such as with their openings **24A**, **24B** facing and/or longitudinal axes extending in a third common direction **D3**. The third common direction **D3** may be at least substantially (e.g., within 20%) perpendicular to **D1** and **D2** in exemplary embodiments, without limitation. Forks **30A**, **30B** of the intermediary transportation vehicle **28** may be inserted into the lift boxes **18A**, **18B** of the units **10A**, **10B** respectively, such as to lift, move, or otherwise manipulate and/or transport the units **10**. The intermediary transportation vehicle **28** may comprise, for example without limitation, a pallet jack, forklift, combinations thereof, or the like. The intermediary transportation vehicle **28** may be manually operable and/or at least partially autonomous.

For example, the forks **30** may move in substantially a direction D4, which may at least substantially (e.g., within 20%) oppose the direction D3 for insertion into the lift boxes **18**, and in the direction D3 to be removed from the lift boxes **18**.

The lift boxes **18** may have a depth (e.g., along longitudinal axis extends into the units **10**) sufficient to accommodate all, at least a majority, and/or substantially all (e.g., >80%) of the forks of the intermediary transportation vehicle **28**. The lift boxes **18** may be sized to provide tolerances for various size and/or shape forks, lateral or other movement of the intermediary transportation vehicle **28**, combinations thereof, or the like.

The lift boxes **18** may be sized according to one or more generally accepted standards for forks of intermediary transportation vehicle **28**. Alternatively, or additionally, the lift boxes **18** may be sized to extend all, or substantially (e.g., >80%) all of a length of the bases **16**.

The bases **16**, such as with the lift boxes **18**, may be used to secure the units **10** to the common surface **32**, such as for packaging and/or transportation, and/or a ground or other surface for final installation, such as but not limited to a sidewalk. For example, without limitation, the bases **16**, such as the platforms **20**, may comprise one or more apertures for receiving bolts or other fasteners. In exemplary embodiments, without limitation, four apertures for four bolts may be provided at substantially four corners of the generally rectangular shaped platform **20**. However, various number and/or arrangement of apertures may be utilized for various types of fasteners in various size and/or shape platforms **20** or other base **16** components. The lift boxes **18** may be integrated with the units **10**. For example, without limitation, the lift boxes **18** may provide part of the structure **14** and/or bases **16** for the units **10**. The lift boxes **18** may remain with the units **10** when installed. The lift boxes **18** may serve to at least partially elevate the electronic display subassemblies **12**. In these ways, the lift boxes **18** may serve multiple purposes.

Any embodiment of the present invention may include any of the features of the other embodiments of the present invention. The exemplary embodiments herein disclosed are not intended to be exhaustive or to unnecessarily limit the scope of the invention. The exemplary embodiments were chosen and described in order to explain the principles of the present invention so that others skilled in the art may practice the invention. Having shown and described exemplary embodiments of the present invention, those skilled in the art will realize that many variations and modifications may be made to the described invention. Many of those variations and modifications will provide the same result and fall within the spirit of the claimed invention.

Certain operations described herein may be performed by one or more electronic devices. Each electronic device may comprise one or more processors, electronic storage devices, executable software instructions, combinations thereof, and the like configured to perform the operations described herein. The electronic devices may be general purpose computers or specialized computing devices. The electronic devices may comprise personal computers, smartphones, tablets, databases, servers, or the like. The electronic connections and transmissions described herein may be accomplished by wired or wireless means. The computerized hardware, software, components, systems, steps, methods, and/or processes described herein may serve to improve the speed of the computerized hardware, software, systems, steps, methods, and/or processes described herein. The electronic devices, including but not necessarily limited to the

electronic storage devices, databases, controllers, or the like, may comprise and/or be configured to hold, solely non-transitory signals.

5. What is claimed is:

1. A display assembly with an incorporated lift box for a fork of a forklift or pallet jack, said display assembly comprising:

a common structure comprising and/or forming the lift box in a base thereof, said common structure comprising:

a platform forming part of the base and a lower surface of the lift box; and

at least one of:

feet, forming part of the common structure, and extending from a lower surface of the platform; and

apertures provided in the platform outside of a footprint of the lift box for receiving fasteners; and an electronic display subassembly connected to the common structure and comprising a cover layer facing in a first direction and an electronic display layer located rearward of the cover layer;

wherein a longitudinal axis of the lift box extends in a second direction which is at least substantially perpendicular to the first direction.

2. The display assembly of claim 1 wherein: the lift box extends at least a majority of a length of the base.

3. The display assembly of claim 2 wherein: the lift box is configured to accept at least a majority of the fork of the forklift and/or pallet jack.

4. The display assembly of claim 2 wherein: the lift box is configured to accept all, or substantially all, of the fork of the forklift and/or pallet jack.

5. The display assembly of claim 1 further comprising: a second electronic display subassembly connected to the common structure and comprising a cover layer and an electronic display layer, each facing in a third direction at least substantially opposite the first direction.

6. The display assembly of claim 5 wherein: the electronic display subassembly and the second display subassembly are located above, and spaced apart from, the lift box.

7. The display assembly of claim 6 wherein: the electronic display subassembly and the second electronic display subassembly each comprise a directly backlit liquid crystal type electronic display.

8. The display assembly of claim 7 further comprising: additional equipment connected to the common structure, said additional equipment comprising electric vehicle charging equipment and at least one item of equipment for operating the display subassembly and the second electronic display subassembly.

9. The display assembly of claim 6 wherein: said lift box comprises a cuboid shaped void which is open on a side facing at least substantially perpendicular to the first direction and the third direction.

10. The display assembly of claim 1 wherein: the lift box is integrally formed with the common structure.

11. The display assembly of claim 1 further comprising: an open, pass-through area formed by the common structure below the electronic display subassembly and above the lift box.

12. The display assembly of claim 1 wherein: the common structure comprises both of:

the feet, forming part of the common structure, and extending from the lower surface of the platform; and the apertures provided in the platform outside of the footprint of the lift box for receiving fasteners.

13. A system for transporting multiple display assemblies together, each having an incorporated lift box, said system comprising:

first and second display assemblies each comprising: a common structure comprising and/or forming the lift

box in a base thereof; and

an electronic display subassembly connected to the common structure and comprising a cover layer and an electronic display layer located rearward of the cover layer; and

a common surface, where the first and second display assemblies are mounted to the common surface in an arrangement such that each of the lift boxes accepts one of the forks of a forklift or pallet jack, and such that the lift boxes collectively accept the forks of the forklift or pallet jack.

14. The system of claim 13 wherein:

the first and second display assembly are mounted to the common surface such that an open end of the lift box of the first display assembly and an open end of the lift box of the second display assembly face in at least substantially a same direction.

15. The system of claim 14 wherein:

the first and second display assembly are spaced apart from one another at the common surface such that the open end of each of the lift boxes are arranged to accept the forks of the forklift and/or pallet jack.

5

15

25

30

16. A method for transporting display assemblies together the system of claim 13, said method comprising:

extending forks of a forklift or pallet jack into an open end of the lift boxes of the first and second display assembly, where the open end of said lift box of each of the first and second display assembly each face in an at least substantially same direction;

operating the forklift or pallet jack to raise the first and second display assembly together for movement to a new location;

moving the first and second display assembly together to said new location; and

operating the forklift or pallet jack to lower the first and second display assembly together at said new location.

17. A display assembly with an incorporated lift box for a fork of a forklift or pallet jack, said display assembly comprising:

a common structure comprising and/or forming the lift box in a base thereof;

a first electronic display subassembly connected to the common structure and comprising a cover layer facing in a first direction and an electronic display layer located rearward of the cover layer; and

a second electronic display subassembly connected to the common structure and comprising a cover layer and an electronic display layer, each facing in a third direction at least substantially opposite the first direction; wherein a longitudinal axis of the lift box extends in a second direction which is at least substantially perpendicular to the first direction.
